UNITED STATES PATENT OFFICE

JEAN FRANÇOIS ARNOLD, OF PARIS, FRANCE

AUTOMATIC SCREW-THREADING MACHINE

Application filed June 22, 1928, Serial No. 287,543, and in France March 26, 1928.

The present invention relates to screw cutting machines particularly adapted for forming screw threads and points upon wood screw blanks having for its principal object 5 to provide a machine for the automatic handling of the screw blanks and completing the wood screw therefrom in order to increase production and reduce the cost of wood screws, thereby rendering the machine commercially desirable.

With the above and other objects in view, which will be apparent as the description continues, the machine may be said to consist of a screw blank feeding mechanism, a plurality 15 of rotatable chucks for engaging and holding screw blanks which have been fed thereto by the said feeding mechanism, a plurality of tools corresponding in number to the chucks so employed in order to cut the desired screw threads upon the blank and also form a point for the screw and a suitable releasing mechanism, whereby the screws, when completed, may be released from the chucks which support the same and all of said mechanisms being operatively connected to a single drive shaft whereby they will be automatically operated to perform their work at the desired time in order that screw blanks 25 may be fed to the machine and completed therein without any manual aid after the machine has been once set in motion.

The appended drawings which are given by way of example show a constructional form of the said invention and represent an automatic machine for the manufacture of four screws at a time.

Fig. 1 is a general plan view of the machine, Fig. 2 is a longitudinal view without the blank-feeding device. Fig. 3 is a 40 transverse view on a larger scale of the supports for the blanks. Fig. 3^a is a detail sectional view. Fig. 4 is a front view of the tool carrying block on a larger scale. Figs. 45 5 and 6 are front and side views of a blank-feeding device. Fig. 7 shows the delivery of a blank before a chuck. Fig. 8 shows the blank in the chuck. Fig. 9 shows the position of the tool when separated from the blank. 50 Fig. 10 shows the tool engaged with the blank

in order to form the point of the screw. Fig. 11 shows the screw-cutting operation.

1 in the driving shaft of the machine, which is rotated by a suitable mechanism provided with coupling means. The said shaft is 55 mounted in two bearings 2 and 3 (Fig. 1) and drives the auxiliary shafts 4—5—6—7 by means of the worm 8 engaging the worm wheel 9 (Fig. 2). The said shafts rotate at a speed determined by the time necessary for 60 the screw-cutting operation, and are connected together by the bevel gearing 10—11—12 (Fig. 1) and are mounted in the bearings 13—14—15—16—17—18 secured to the base plate 19 (Fig. 2), not shown in Fig. 1. 65 The movement of the shaft 1 is transmitted to preferably four chucks three of which are shown in the drawings at 20—21—22, by the cone clutch 24 and the central pinion 25 keyed to the shaft of the clutch and engaged with 70 both pinions mounted on the shafts of the respective chucks. The said chucks receive the blanks for the screw cutting. The cone clutch 24 is controlled by the cam 26 keyed to the shaft 5 and acting on the lever 27 which 75 is pivoted to the shaft 28 and controls the fork 29 disposed in the groove 30. The said clutch is regulated by the device 31 which allows of bending the lever 27. The chucks shown are mounted on the shafts 32—33—34 80 which rotate in the stocks 36—37—38. The chucks themselves each consist of a hollow head (Fig. 2) to which are pivoted two levers 40 and 41 terminated at the front by two jaws and at the rear by two rollers which when 85 separated will close the said jaws upon the screw blanks. The pivoted levers 40—41 are urged to the rear by a spring, not shown. The rollers are separated by the lengthwise displacement of sleeves 42 comprising a 90 tapered part on which the said rollers can mount. The sleeves 42 are controlled by a double fork 43 coacting with the grooves 44 of the sleeves; said double fork assures an 95 approved rigidity to the sleeves when connected, and is controlled by the lever 45 (Fig. 1) acting on the cam 46 keyed to the shaft 5. In front of the said chucks are disposed a pair of supporting members as indicated at 47—48 and 49—50 respectively (Fig. 2) 100.

adapted to hold the blank and to prevent it from bending by the pressure of the tool during the work. The said supports are movable and can thus be withdrawn when the 5 blanks are placed in the chucks, this being performed in the following manner. The said supports are connected together in pairs by two sliding members 51 and 52 (Figs. 3 and 3^a) which are mounted by dovetails in 10 the guides 53—54 secured to the machine. The guide 52 is cut out to permit the motion of the arms 47^a and 48^a carrying the supports 47—48. The two sliding members are given an opposite reciprocating motion in the vertical direction, this being controlled by a lever 55 situated by the cam 56 on the shaft 6. The said lever pivots on a stationary point 57 and is connected with the guides 51—52 by the links 58 and 59. Opposite the four 15 chucks are mounted the four tool holders 60—61—62—63 secured in the two blocks 64—65 which are held by a frame consisting of the uprights 66—67 (Fig. 4) mounted on a base plate 68. The blocks 64 and 65 are laterally slidable in the interior of said uprights in dovetail guides formed in the plate 68 and the cross-pieces 69—70 (Fig. 1). The motion of the tool-carrying blocks is controlled by two members 71—72 forming a double 20 wedge which may press upon the rollers 73—74—75—76 (Fig. 4) and thus separate the tool-carrying blocks 64 and 65 which are urged towards the centre by springs 77. The members 71—72 are connected together by a 25 bar 78 which is given a vertical reciprocating motion. This motion is controlled by a lever 79 (Figs. 1 and 2) pivoted to the axle 80, the connection with the bar being assured by a block 85 in which the bar and the lever 30 79 are freely slidable. The lever 79 is actuated by a cam 81 whereby the lever 79 can be moved in both directions to prevent the separation of the blocks by the reaction of the tools during the work. The device consisting 35 of the tool carrying blocks and the base plate 68 is slidable in a guide which is secured to the machine frame for the lengthwise motion of the tools. This motion is obtained by means of the double cam 83 mounted on the 40 shaft 7 and acting both ways upon the lever 84 which is secured at 68^a to the plate 68 (Fig. 4) of the tool-carrying blocks. The tool-holders are traversed by a conduit 86 (Fig. 2) supplying oil through a nozzle upon the tool 45 during the work (Fig. 4). The pump is driven by the machine and assures a constant supply of oil for this purpose.

The tool consists in each case of two distinct parts, whereof one 60^a serves to form the 50 point of the screw (Fig. 10) and the other 60^b to form the thread (Fig. 11). The tools operate as follows. The disengaged tool advances in order to take the proper position. It then engages the blank and commences to 55 form the point (Fig. 10), then the thread-

cutting tool commences to operate, moving from the top of the screw towards the point. (Fig. 11). After this operation, the tool commences a second or finishing cut, whereby the thread and the point are terminated according to the proper outline. The device for feeding the blanks to the chucks comprises two feeding recipients 87 symmetrically disposed and connected by a trough which supplies them by gravity with the blanks. Figure 1 shows (for the sake of clearness) only one of the feeding devices, and Figures 5 and 6 show details of said device. The recipient 87 containing the blanks has leading therefrom two inclined chutes 88 and 89 ending adjacent the respective troughs 90—91 through which the blank travels in a proper position to attain the respective chucks. The said chutes consist of two strips between which are slidable the said blanks 85 which have the vertical position and are retained by their upwardly extending heads. The inclination of the said chutes is such that the blanks will descend by gravity. A piston 92 ending in the said slides is movable and is given a vertical reciprocating motion in the recipient 87 in such manner as to collect the blanks in the vertical position with the head upwards, for the supply of the said chutes. The device is operated by the cam 93. The members 90—91 which receive the blanks individually are secured to a delivery slide 94 which is given—by a cam 95 (Fig. 5)—a reciprocating motion perpendicular to the axis of the machine, the cam 95 acting 90 upon a roller 95^a secured to the slide 94. A tappet 96, secured to the said slide, draws forward at the end of the stroke and to a suitable degree, by its action on the stop 97, a rod 98 secured to said stop and slidable in supports 100 mounted on the machine frame. The rod 98 actuates two members 99 and 100 whereof each comprises two points in opposite position and spaced by an amount equal to the diameter of the blanks so that at each reciprocating movement of the slide 94, the said points will allow a blank to drop, which will be placed horizontally on the members 90 and 91. Adjacent the said members and adapted to be drawn forward by the slide, are 110 disposed two push-pieces 101 and 102 (Fig. 6). The said push-pieces are given, by the cam 103 and lever 104, a second straight movement perpendicular to the first, i. e. to the axis of the machine. This movement serves 115 to supply the blanks to the chucks.

The operation is as follows:

The blanks in one of the feeding recipients 87 are delivered by the pistons 92 to the chutes 88—89. The blanks descend by their own weight and are stopped by the set of pointed members 99 and 100 which act by their alternate motion to feed only a single blank at a time to the members 90—91 of the feeding slide. This latter advances 130

transversally so as to supply the blanks in line with the chucks 20—21—22. The push pieces 101—102 then feed the blanks between the open jaws 40 etc. of the chucks 20 etc. (Fig. 1). At this time the jaws which are controlled by the lever 45 will close while the feeding slide 94 is withdrawn. At the same time the clutch 24 engages the shaft 1 with the device controlling the chucks, and the chucks 10 commence to turn, so that the tool-carrying blocks will move lengthwise by the action of the double cam 83 (Fig. 2). When they attain the end of their stroke, the said tools, due to the action of the lever 79, will approach 15 the blank and will begin to form the point (Fig. 10). When this cut is finished, the tools are removed, they return to the initial working position, and then begin a second or finishing stroke under the combined action 20 of the cams 81 and 83. The screw is thus finished, and the jaws of the said chucks will open and will allow the screw to drop into a recipient, while the chucks are stopped; the same cycle of operations then continues.

25 The outline of the different cams and of the several devices are suitably determined for the execution of the said work.

Obviously, the said apparatus is susceptible of various modifications without departing 30 from the limits of the invention. The details of the design and construction may also be suitably modified.

I claim:

1. An automatic wood screw cutting machine comprising in combination a drive shaft, a plurality of screw blank receiving chucks, a clutch for operatively connecting said chucks to said drive shaft whereby they will be caused to rotate therewith, a screw blank feeding mechanism adapted to deliver the blanks to said chucks, an auxiliary shaft operatively connecting said feeding mechanism with said drive shaft, means for operatively connecting said auxiliary shaft with 45 said clutch and adapted to operate the latter with rotation of said auxiliary shaft to operatively connect the chucks to the drive shaft, a plurality of cutting tools and means for operatively connecting said cutting tools with 50 said drive shaft whereby they will be automatically brought into and out of engagement with the screw blanks supported by said chucks.

2. An automatic wood screw cutting machine comprising in combination a drive shaft, a plurality of screw blank receiving chucks, a clutch operatively connecting said chucks with said drive shaft, a cutting tool for each chuck, means for operatively supporting said cutting tools in front of said chucks, a screw blank feeding mechanism adapted to deliver the screw blanks to each of said chucks, an auxiliary driven shaft for operatively connecting said screw blank feeding mechanism with said drive shaft, means

for operatively connecting said clutch with said driven shaft operatively connected to the screw blank feeding mechanism to time the operation of the latter in relation to the operation of the chucks, and means for operatively connecting said cutting tool supporting means with said drive shaft whereby the tools thereof will be brought into and out of engagement with the screw blanks carried by said chucks. 70

3. An automatic wood screw cutting machine comprising in combination a drive shaft, a plurality of rotary chucks, a clutch for operatively connecting said rotary chucks to said drive shaft, an auxiliary shaft operatively connected to said drive shaft and driven thereby, cam means keyed to said auxiliary driven shaft and rotating therewith, and connecting means between said cam and clutch, whereby the latter is operated through 80 the rotation of said auxiliary driven shaft.

4. In automatic wood screw cutting machine comprising in combination a drive shaft, a plurality of rotary chucks, a clutch for operatively connecting said rotary chucks to said drive shaft, an auxiliary shaft operatively connected to said drive shaft and driven thereby, a screw blank feeding mechanism adapted to deliver the screw blanks to each of said chucks and operated by said auxiliary driven shaft, and means for operatively connecting said clutch to said auxiliary driven shaft to time the operation of the clutch in relation to the operation of the screw blank feeding mechanism. 90

In witness whereof I have hereunto set my hand.

JEAN FRANÇOIS ARNOLD.
